UNITED STATES PATENT OFFICE.

CHARLES D. ROGERS, OF PROVIDENCE, RHODE ISLAND.

FIRE-ALARM APPARATUS.

SPECIFICATION forming part of Letters Patent No. 340,618, dated April 27, 1886.

Application filed June 20, 1883. Serial No. 98,687. (No model.)

To all whom it may concern:

Be it known that I, CHARLES D. ROGERS, of the city and county of Providence, in the State of Rhode Island, have invented certain new and useful Improvements in Fire-Alarm Apparatus; and I do hereby declare that the following specification, taken in connection with the drawings furnished and forming a part thereof, is a clear, true, and complete description of my invention.

My said improvements relate to that class of fire-alarm systems which involve the employment of a central or headquarters' station, and a series of public district boxes or alarm-stations at which alarms can be turned in whether the central station be provided with automatic apparatus for distributing the alarm or with simple annunciators for observation by attendants, it being well known that the district boxes in one case necessarily involve clock-work or rotating mechanism of some kind, and that in the other case a simple push-button may be relied upon. However, the main fire-alarm system may be arranged, and however the district alarm-boxes may be constructed and operated my improvements are applicable thereto, with only such variations as would be incident to the special conditions involved in each case.

So far as my knowledge extends all district fire-alarm boxes as heretofore arranged, whether located in streets or in buildings, are for the purpose of obviating mischievous false alarms securely locked, the key or keys of each box being in the custody of one or more neighbors.

It is well known that expensive delays in sounding alarms frequently occur, not only because the custodians of the keys are seldom widely known, but also because they are sometimes not available, and still further because of the remoteness of the box from the fire, as well sometimes of the ignorance of parties first cognizant of a fire as to a proper course of action in connection with the district boxes. It is also well known that when district boxes are located within buildings connected with large manufacturing establishments it too frequently occurs that access thereto is temporarily obstructed by doors liable to be locked, thus necessitating a loss of time.

The object of my invention is to enable a public fire-alarm box to be fully controlled at a distance and to economize in time in turning in alarms. To these ends I employ one or more local electric circuits connected with an alarm-box controller, which can be operated by means of keys or buttons in said circuits, and thereby enable alarms to be turned in precisely as if said box had been operated by hand in the usual manner; or, in other words, to turn in an ordinary alarm, or in emergencies to turn in a repeated or general alarm.

My apparatus differs from certain prior contrivances by which private establishments have been connected by a local circuit with a public alarm-box in that they admitted of a single or ordinary alarm only, and having been once thus operated they had to be reset or adjusted at the alarm-box before they could be again operated, whereas with my apparatus an alarm through the same box can be many times repeated, if need be, and the boxes need only be visited at more or less frequent intervals for winding. Even when a single private establishment is thus connected with a public alarm-box it is obviously important, as in cases of great danger, that the box be capable of being again operated through the same local circuit without first visiting the box and readjusting the box-controller; but it is of still greater importance when, as now arranged by me, any one box-controller is or may be included in a public circuit embracing many different premises, and more especially when, as by me for the first time, a box-controller can be included within any number of separate local circuits, both public and private, so that consecutive alarms can be turned in from the same box, not only from all the circuits, but from any number of points in each circuit.

At the district box, which is sometimes called the "fire-alarm station," I employ within a box in what is known as the "Gamewell System," a mechanical motor or box-controller, electrically controlled, which performs the same service in depressing and releasing a hand-lever which a person would perform should he, after opening a box, turn in an alarm, and when an alarm has been sounded the apparatus within the box is left as before, in condition for another alarm. If a box con-

tains a simple push-button, similar mechanism may be employed. If the district box contains a hand-crank for rotating a contact or break wheel, a mechanical motor is requisite, 5 as in the Gamewell system; but it is so applied as to impart the requisite movement of the contact wheel, instead of merely deflecting a lever. In accordance with my invention the local circuits may be either opened or closed, metallic or ground, and the devices employed in 10 said circuits for making or breaking a current therein may be pivoted switches, or spring-keys, or push-buttons, or any other well-known arrangements for controlling contact-points, 15 and said local circuits can at one or more points be also placed under the control of such well-known automatic apparatus as is in various ways operated by thermometric influences. Recognizing the importance of guarding 20 such local circuits as far as possible against mischievous tampering and false alarms, I provide for so protecting the several push-buttons or switches in each local circuit that if any one or more of them be operated for giving 25 an alarm the fact thereof cannot be concealed, thus enabling the occupants of premises from which an alarm has been sounded to be held to a strict accountability.

It has heretofore been proposed to employ 30 glass-covered casings for thus protecting a fire-alarm button or key, thus requiring the breaking of the glass before sounding an alarm; but I obviate the expense of glass covers and the danger incident to hastily breaking them 35 by employing paper seals for guarding a novel key box or casing to which they may be readily applied. It has also been heretofore proposed, in connection with the fire-alarm boxes coupled directly with central stations, to provide 40 paper seals secured to the under side of the cover of the box by means of special fastening devices—such as clamping-rings, screws, and thumb-nuts—all of which devices are obviated by me, because the mere act of closing 45 the cover properly secures my seal in position, and the mere opening of the door leaves a broken seal accessible to ready displacement, and enables a new seal to be promptly inserted in a proper position to be confined by 50 the door when it is next closed.

To more particularly describe my invention, I will refer to the accompanying drawings, in which—

Figure 1 is a graphic illustration of a 55 public fire-alarm system including the headquarters or central station, the usual bell-towers, district boxes or alarm-stations, and my local circuits, in combination with said boxes, as employed in accordance with my invention. Fig. 2 is an interior front view of one of the station-boxes. Fig. 3 is a rear side view of the box-controller detached from the box. Fig. 4 is a top view of said box-controller. Figs. 5 and 6 are respectively front and 60 sectional views of a guarded local-circuit key. Fig. 7 represents a paper key-seal detached.

In Fig. 1 the fire-alarm headquarters A, bell-towers B, and district boxes or fire-alarm stations C, D, E, and F are to be understood as illustrating, so far as is required for the purposes 70 of this specification, a public fire-alarm apparatus embodying the well-known Gamewell system, each box having, as shown in Fig. 2, a spring hand-lever, G, which, when depressed, permits the clock-work at the rear of the face-board G' to rotate a break-wheel, and thereby 75 communicate to headquarters and to the bell-towers the number of the box. My improvements involve the addition to such or similar systems of one or more local electric circuits 80 to one or more of the district boxes. As here shown, the alarm-boxes C, D, and E are respectively provided with metallic local circuits, and box F is provided with two separate local earth-circuits. In each local circuit 85 more or less of the adjacent principal buildings are included, especially such as may be most remote from the alarm-box, so that in the event of a fire on any of said premises an alarm may be communicated through the 90 proper box to headquarters, as if the box had been visited, opened, and operated.

Referring now to Figs. 2, 3, and 4, I will describe the box-controller or local-circuit motor H as preferably constructed by me. It 95 embodies a spring and winding-arbor, a, in the spring-case a', a star-wheel, b, on said arbor, a vibrating ball-escapement, c, which engages with the star-wheel to serve as a governing device for limiting the speed of rotation of the 100 spring-arbor when free to rotate, and a stop-disk, d, which is mounted upon the spring-arbor a and rotates with the star-wheel. The stop-disk has its stop-notch or shoulder at d', and this abuts against a stud, d'', and limits 105 the disk to one revolution. The stud d'' is mounted upon an armature-lever, e, provided with a tension-spring, e', and said armature is controlled by the electro-magnet e'', the helices or coils of which are connected in a well-known 110 manner with the local circuits f. The stop-disk d, as before stated, revolves with the winding-arbor a, and it is provided with a crank-pin, d', to which the rod or link g is connected, so that when the stop-disk makes 115 one revolution it causes the link g to be moved vertically downward and then back again. The outer end of said link has a strap or slot, g', through which the spring-lever G of the 120 alarm-box projects, and therefore when said rod is reciprocated to and fro said lever is deflected, permitting the box to operate as if an alarm had been turned in by hand at the box. The slot at g' enables the lever G to be freely 125 deflected by hand without interfering with the motor H, and a similar substantially flexible connection between said motor and lever may be provided for by the use of a chain or strip of spring metal, but it should have means for convenient longitudinal adjustment, and the 130 link or rod shown is constructed for that purpose in two lengths, and connected by a sleeve-

nut, g^1 , tapped to receive right and left hand threads which are cut on the adjacent ends of the link.

In the drawings, Fig. 1, the alarm-boxes C, 5 D, and E have metallic local circuits f , and said boxes respectively sound, for instance, Nos. 23, 24, and 25. A description of one of these circuits will serve for all. The local metallic circuit f for box C includes four buildings, h , h' , h^1 , and h^2 . In the building h the battery i is located, serving for the entire circuit. In each building there is a circuit-key, k , and these are in each instance coupled into the circuit, so that either will cause the 15 motor or box-controller H to turn in an alarm, and, inasmuch as all of them communicate with the same box, no confusion can possibly occur. In either of said buildings a thermostatic apparatus can be employed, as at k' , for 20 automatically turning in an alarm through a public district box.

Instead of the metallic circuits I can employ radiating ground-circuits, as illustrated in connection with box F. In this case, as 25 before described, the battery i is located in the building nearest the box on the circuit, and the several circuit-keys k are each connected with the line and with a local ground, f' , and one terminal of the helix in the motor H is also grounded at f^1 . With these grounded 30 circuits the alarm would be properly turned in even if every key on all the circuits should be operated at once, although of course only the nearest keys would really serve their purpose. With these radially-grounded circuits 35 a battery may be employed on each; or if a battery be located in the box or closely adjacent thereto all of the circuits could merge at the battery and enable it to serve for all.

40 It will be seen that my motor or box-controller may be included in more than one local circuit, as shown in connection with the box F, with which one grounded circuit includes three buildings, and a second similar circuit 45 only one building, and should an alarm be needed in either circuit after an alarm had been sounded from the other it can be done, thus providing for the required general alarm for indicating a special emergency at that particular locality.

I guard against a wrongful use of the alarm-keys in the local circuit in a simple and novel manner.

As seen in Figs. 5, 6, and 7, I employ a 55 paper seal, l , which is a thin paper disk, inscribed, stamped, or printed in any way to avoid wrongful imitation, and these seals are to be only procurable from and furnished by an officer of the public fire department, and 60 he also has the only key which fits the lock of the hinged cover m on the front of the casing, which contains the circuit-key k and its button, this latter being accessible to the finger only by way of a central opening in the cover 65 m . The seal l is interposed between the cover m and the casing so as to wholly cover or

guard the button of the circuit-key, and said seal is securely held by the puncturing-points m' , so that it will be practically impossible for a circuit-key to be operated without rupturing a seal, thus clearly locating the source of an alarm turned in on any one of the local circuits.

70 While I prefer a mechanical box controller or motor substantially as described, it is obvious that a simple electro-magnet may be applied to a Gamewell box for lifting the usual detent-lever from the stop-wheel and allowing the box to be sounded without departure from certain features of my invention; but 75 this would involve more or less reorganization of the mechanism now used in said boxes. In such boxes as have a hand-crank my motor H can be employed by causing the link g to serve as a rack to engage with a ratcheted gear on 80 the hand-crank-shaft, and for such boxes as contain a mere push-button said link g , if connected to a bell-crank lever, would cause 85 one end of said lever to press upon the button, and so turn in an alarm.

90 My invention will be found of great value in the suburbs of towns and cities where alarm-boxes are widely separated, and in thickly-settled localities, where prompt alarms are all the more important, much time will be saved 95 by placing each public alarm-box practically within reach of more or less of the most important establishments in its vicinity. In some cases it will be desirable to connect a gong, n , with the motor H , so that simultaneously with the turning in of an alarm on any local circuit the immediate neighborhood may be aroused, and for this service the ball of the 100 governor may be relied upon as a striker.

Having thus described my invention, I claim 105 as new and desire to secure by Letters Patent—

1. The combination, substantially as hereinbefore described, of a public fire-alarm box provided with means for operating it by hand in a usual manner, a box-controller therein 110 which embodies driving mechanism and electro-magnet, and a stop which normally restrains said mechanism from continuously operating, but which is released therefrom and reapplied through said magnet, and one or 115 more local electric circuits which include the coil of said magnet and are provided with keys or switches, whereby the box may be operated, as usual, by hand, and whereby said driving mechanism may be repeatedly released 120 by the manipulation of any one or more keys in any one or all of the circuits, and enable repeated alarms to be turned in from one or more points in any one circuit or in different local circuits.

125 2. The combination, in an electric fire-alarm system, of a public district or station alarm-box electrically communicating with fire-alarm headquarters and provided with means for operating it by hand in a usual 130 manner, and a box-controller in said box containing driving mechanism, a stop-disk which

4 by its rotation operates the box and can be rotated in but one direction, an electro-magnet, a stud normally engaged with said stop-disk, but released therefrom by said magnet, and 5 one or more local electric circuits including said electro-magnets, and provided with keys or switches, whereby said magnet may be made to release said disk and enable an alarm to be repeatedly turned in from any one or 10 more keys in either circuit or successively turned in from keys in different circuits.

3. The combination, with a complete fire-alarm box provided with means for operating it by hand in a usual manner, of the mechanically-driven stop-disk, the reciprocating link 15 by which said disk is loosely connected to the box-operating lever, the stop for said disk, the electro-magnet by which said stop may be moved, and one or more local electric circuits 20 including the coil of said magnet and provided with keys, substantially as described, whereby said box can be operated in the usual manner, or one or more successive alarms turned

in either from one or more keys on the same local circuit or from keys in different circuits. 2

4. The combination, with a complete fire-alarm box provided with means for operating it by hand in a usual manner, of a box-controller operated through local electric circuits, and embodying driving mechanism having a star-wheel and a vibrating-governor operating as 3 a signal-striker, substantially as described.

5. The combination, with a public fire-alarm box provided with means for operating it by hand in a usual manner, of a box-controller 3 embodying driving mechanism controlled through a local electric circuit, and keys in 4 said circuit, which are housed within casings having locked covers, and are guarded by paper seals clamped by said covers, substantially as described.

CHARLES D. ROGERS.
